(57) **CLAIM**

The ornamental design for a multimedia phone, as shown and described.

DESCRIPTION

FIG. 1 is a front elevational view of a multimedia phone showing our new design;

FIG. 2 is a rear elevational view thereof;

FIG. 3 is a left-side elevational view thereof;

FIG. 4 is a right-side elevational view thereof;

FIG. 5 is a top plan view thereof; and,

FIG. 6 is a bottom plan view thereof.

The diagonal lines with alternating thick and thin lines as shown in FIG. 1 illustrate the portions of the design that are white in color.

1 Claim, 5 Drawing Sheets
